SELF-SHARPENING SAFETY RAZOR

William F. Eckert, Mauch Chunk, Pa.

Application August 7, 1951, Serial No. 240,713

5 Claims. (Cl. 30—36)

1

This invention relates to safety razors of a type having a single cutting edge, and in particular a safety razor having a substantially U-shaped head, the inner surface of which is lined with a leather strip and the blade which is clamped between the open edges of the head in the shaving position by a handle is provided with holders on the ends by which the blade is reciprocated in the head to sharpen the cutting edge thereof.

The purpose of this invention is to provide a safety razor in which the blade thereof is used for an indefinite time.

Various devices have been provided for sharpening blades of safety razors, however, it is difficult to combine sharpening elements with the razor head without interfering with normal use of the razor. With this thought in mind this invention contemplates a safety razor in which the toothed guard is formed on the edge of the head and the head is extended in the form of a U whereby with the inner surface lined with a sharpening element the blade may be sharpened by drawing both sides of the cutting edge thereof along the sharpening element.

The object of this invention is, therefore, to provide means for forming the head of a safety razor whereby a sharpening device may be incorporated therein.

Another object of the invention is to provide a safety razor in which sharpening elements may be incorporated in the head without necessarily enlarging the head.

A further object of the invention is to provide a self-sharpening safety razor which is of a simple and economical construction.

With these and other objects and advantages in view the invention embodies a safety razor in which the head is formed of a flat strip of spring steel bent midway of its length to form a U and with a loop extended from one arm around the other to limit opening movement thereof, a razor blade having holders on the ends freely positioned in the head whereby the blade is actuated to contact sharpening surfaces in the head for sharpening, and a handle threaded in the loop extended from one arm of the head and positioned to clamp the opposite arm of the head against the arm from which the loop extends for clamping a razor blade in cutting position between the arms of the head.

Other features and advantages of the invention will appear from the following description taken in connection with the drawings wherein:

Figure 1 is a side elevational view illustrating

the improved safety razor with the parts in the shaving position.

Figure 2 is a similar view looking in the opposite direction and showing the shaving head or blade clamping parts holder in section.

Figure 3 is a plan view of the razor with the parts as shown in Fig. 1.

Figure 4 is an end elevational view also with the parts as shown in Fig. 1 and showing the threaded end of the handle in the position of clamping a blade between the arms of the head.

Figure 5 is a sectional plan showing the razor blade in the cutting position on the lower arm of the head.

Figure 6 is a side elevational view similar to that shown in Fig. 2 showing the blade in the sharpening position with the upper side of the cutting edge held against the inner surface of the upper arm of the head for sharpening.

Figure 7 is a longitudinal section through the head of the razor showing the position of the blade reversed wherein the lower side of the cutting edge is in engagement with the inner surface of the lower arm of the head.

Figure 8 is an end elevational view similar to that shown in Fig. 4 with the blade released as in the position shown in Fig. 7.

Figure 9 is a side elevational view of the razor with the bar forming the lower side of the loop extended from one arm of the head removed whereby the blade may be removed from the head or holder.

Figure 10 is a cross section taken on line 10—10 of Fig. 9 showing the upper arm of the head with end sections of the loop which extends around the opposite end extended therefrom.

Referring now to the drawings wherein like reference characters denote corresponding parts the improved safety razor of this invention includes a blade 10 having thumb and finger gripping holders 11 and 12 at the ends of a bar 13, a U-shaped head formed of spring material and having an upper arm 14 and a lower arm 15 between which the blade 10 is positioned, a lining 16 providing a continuous sharpening surface on the inner surfaces of the arms of the U-shaped head, and a handle 17 threaded in a bar 18 which forms a base of a loop extended from the upper arm 14 of the back and which is connected to the arm 14 with end sections 19 and 20. The ends of the bar 18 being removably attached to the ends of the end sections by screws 21.

The blade 10 is of the conventional single cutting edge type and, in the design shown the blade is provided with a U-shaped reinforcing bar 13

on the ends of which the holders 11 and 12, which are in the form of segments are positioned. The holders may be provided with gripping surfaces 22 and 23, respectively.

With the holders 11 and 12 gripped between the thumb and forefinger of a hand and with the lower arm 15 of the head released, as illustrated in Fig. 6, the blade 10 is drawn rearwardly with the upper side of the cutting edge sliding over the leather lining strip 16, as illustrated in Fig. 6. The blade is drawn away from the head and at the end of this movement the blade is moved forwardly with the cutting edge held between the arms 14 and 15 whereby in the next movement the position of the blade is reversed whereby the lower side of the cutting edge slides over the lining strip 16, as shown in Fig. 7.

The lower arm 15 of the U-shaped head is provided with comb teeth 24 forming a guard and this edge of the arm curves downwardly, as illustrated in Fig. 6.

The handle 17 is provided with a threaded stem 25 having a head 26 thereon and with the stem threaded in the bar 18 the end of the lower arm 15 may be moved upwardly against a blade 10 positioned between the arms whereby the blade may be positively clamped in operative or cutting position, as illustrated in Figures 1 and 2.

With the parts arranged in this manner the blade may be used continuously with the blade clamped between the open ends of the arms of the head for use and freely positioned therein for sharpening.

When it is desired to remove and replace the blade the screws 21 are removed and the bar 18 dropped downwardly, to the position shown in Fig. 9 whereby the blade may be taken off and replaced.

It will be understood that modifications may be made in the design and arrangement of parts

without departing from the spirit of the invention.

What is claimed is:

1. A safety razor comprising a strip of material bent midway of the length thereof forming substantially parallel arms providing a U-shaped head, one arm of said head having a loop extended therefrom and positioned around the other arm thereof, a sharpening surface on the inner surface of the head, a handle having a threaded stem positioned with the stem threaded in the loop and adapted to engage said other arm of said head for moving said arm relative to said one arm of said head, and a safety razor blade having gripping elements on the ends positioned in the head and adapted to be clamped by the handle between the arms of the head for shaving.

2. A safety razor as described in claim 1 wherein the inner surface of the U-shaped head is lined with a strip of leather providing the sharpening surface.

3. A safety razor as described in claim 1 wherein the stem of the handle is provided with a head to prevent the handle being accidentally removed from the loop.

4. A safety razor as described in claim 1 wherein the loop extended from one arm of the head is provided with a removable section to facilitate removing the blade from the head.

5. A safety razor as described in claim 1 wherein the arm of the head extended through the loop is provided with arcuate guard teeth formed to correspond with the comb of a safety razor.

WILLIAM F. ECKERT.
